CONVEYER

J. Lowell Gibson, Dayton, Ohio, assignor to General Motors Corporation, Dayton, Ohio, a corporation of Delaware

Application February 3, 1950, Serial No. 142,240

5 Claims. (Cl. 198—131)

1

This invention relates to conveyors and particularly to conveyors of the endless type.

An object of my invention is to provide an improved endless conveyor of great strength and low manufacturing cost for use in bottled beverage storing, cooling and dispensing apparatus.

Another object of my invention is to provide a conveyor with a plurality of bottle-receiving and carrying receptacles formed of two half members secured together by a means which connects the receptacles in endless relation to one another and also provides a hinge between adjacent receptacles.

A further object of my invention is to provide a conveyor with a plurality of substantially cylindrical-shaped bottle-receiving and carrying receptacles by turning one of two similarly formed semi-cylindrical members of each receptacle over into face-to-face relation with the other member and locking the same to one another and to the members of adjacent receptacles of the conveyor by a common connecting means which forms a hinge between the adjacent receptacles.

A still further object of my invention is to provide a continuous conveyor comprising a plurality of hinged together open end receptacles with link means between the hinges of adjacent receptacles which link means extends across one of the open ends of each receptacle and forms a stop for a bottle to be received in the receptacle.

Further objects and advantages of the present invention will be apparent from the following description, reference being had to the accompanying drawings, wherein a preferred form of the present invention is clearly shown.

In the drawings:

Fig. 1 is a plan view of one of a plurality of elongated semi-cylindrical shaped sheet metal members employed in the construction of my improved conveyor;

Fig. 2 is a side view of the member disclosed in Fig. 1;

Fig. 3 is an end view of the semi-cylindrical member looking in the direction of the arrow in Fig. 2;

Fig. 4 is an end view of two of the members shown in Figs. 1, 2 and 3, placed together to provide a substantially cylindrical receptacle;

Fig. 5 is a side view of the receptacle disclosed in Fig. 4 and shows a portion of other similar receptacles adapted to be placed into association therewith;

Fig. 6 is a view of a portion of a continuous conveyor formed by connecting a plurality of the cylindrical receptacles shown in Figs. 4 and 5 together;

2

Fig. 7 is an end view of the portion of the continuous conveyor shown in Fig. 6; and

Fig. 8 is a view on a reduced scale showing a continuous conveyor constructed in accordance with my invention and looped over suitable pulleys or the like.

Referring to the drawings, for illustrating my invention, I have shown in Fig. 1 thereof an elongated sheet metal member 11 of substantially semi-cylindrical shape in cross-sectional contour. Member 11 is preferably stamped from sheet aluminum and is formed to provide straight opposite marginal edges 12 and 13, ends 14 and 15 and bent intermediate the edges 12 and 13 into an arcuate or semi-cylindrical shape (see Fig. 3). The member 11 is provided with integral spaced apart extensions along its marginal edges 12 and 13 which extensions are rolled or formed into substantially the shape of eyelet-like bearing portions 17 and 18 projecting outwardly from the opposite marginal edges 12 and 13 respectively. The spaced apart eyelet-like bearing portions 17 projecting outwardly from marginal edge 12 of member 11 are arranged in staggered relation to the portions 18 projecting from the marginal edge 13 of member 11 for a purpose to be herein-after described. It will be noted that there are three of the eyelet projections 17 along the edge 12 of member 11 and only two such projections 18 along the marginal edge 13. It will also be noted that one of the projections 17 is located at the end 14 of member 11 while another projection 17 is placed a short distance from the end 15 of member 11. The two longitudinally spaced apart projections 18 are located opposite the spaces between the end and intermediate projections 17. A portion at the edge of each end 14 and 15 of member 11 is deformed or flanged as at 19 to provide a curved lip which extends throughout a part of the semi-cylindrical contour thereof.

In assembling the conveyor of the present invention I turn one of the members 11, formed or shaped as described, such for example, as member 11a, over into face-to-face relation with and rotate the same 180 degrees relative to another of the similar or identical members 11, as shown in Fig. 4 of the drawings, to form a substantially cylindrical shaped pocket or receptacle generally represented by the reference character 21. Instead of first turning member 11a over and thereafter rotating the same 180 degrees about a vertical axis I may place member 11a in face-to-face relationship with member 11 by merely rotating it 180 degrees about a horizontal axis to bring the eyelet-like projections on similar

marginal edges of each member in alignment with one another. It is to be understood that the two sheet metal members 11 and 11a of receptacle 21 are identical in size, shape and in the number and arrangement of the marginal eyelet projections and I am merely employing the suffix *a* to certain numerals to more clearly describe and illustrate the invention. It is to be further understood that the term "face-to-face" as used in the present description applies to the inner surface or face of members 11. By placing the one member 11a into face-to-face cooperative relation with a companion member 11 as described, the eyelet-like bearing portions 17a along the marginal edge 12a of member 11a and the eyelet portions 17 along the marginal edge 12 of member 11, are disposed on the same side of receptacle 21 and are in alignment with one another. Likewise eyelet-like bearing portions 18a along the marginal edge 13a of member 11a and eyelet portions 18 along the marginal edge 13 of member 11 are disposed on the same side of receptacle 21 and are in alignment with one another (see Fig. 5). Thus the end 14 of the one member 11 is disposed directly across from the end 15 of the other member. The spaced apart and staggered arrangement of the eyelet-like bearing portions 17, 18, 17a and 18a along the marginal edges of members 11 and 11a of the cylindrical bottle receptacle 21 provides alternate spaces, indicated by the reference character 23, along one side of receptacle 21 and alternate spaces, indicated by the reference character 24, along the opposite side of receptacle 21 (see Fig. 5). A plurality of members 11a are turned and rotated and placed into cooperation with companion member 11 to provide a series of the receptacles 21 as shown in Fig. 5 of the drawings. Thereafter one of the adjacent receptacles 21a is moved toward receptacle 21 to position the eyelet-like projections 18 and 18a thereon in the spaces 23 so that the eyelet-like portions 17 and 17a on receptacle 21 align with the portions 18 and 18a on the receptacle 21a. Another receptacle 21b adjacent receptacle 21 is moved toward receptacle 21 to position the eyelet-like portions 17 and 17a thereon in the spaces 24 on the opposite side of receptacle 21. After positioning the series of receptacles 21 in cooperation with one another as just described, a pin or bolt is pushed through the opening in aligned eyelet-like bearing portions 17, 17a, 18 and 18a of adjacent receptacles to connect the series thereof into the form of an endless chain.

Referring now to Fig. 6 of the drawings I show a fragment of the endless chain and it will be noted that the eyelet-like portions 17, 17a, 18 and 18a of the members 11 of receptacles 21 receive a bolt 26 which locks each of the members 11 and 11a of receptacles 21 in face-to-face relation with one another. The bolts 26 include a head 27 at their one end and their opposite end is riveted over as at 28 to prevent removal of the bolts from the conveyor. It should be noted that the bolts 26 in addition to locking the semicylindrical shaped members 11 and 11a of each receptacle 21 together, also provide a hinge between adjacent receptacles 21 to permit a pivotal movement of one receptacle 21 relative to an adjacent receptacle of the series thereof. I have provided rigid connecting means between adjacent pins or bolts 26 of the continuous conveyor which means serves a double purpose. Referring to Figs. 6 and 7 I show a plurality of metal links 29 along one longitudinal side of the conveyor. One link 29

extends across the open-back of each of the cylindrical receptacles 21 and is provided with a hole at each of its ends which receives adjacent pins or bolts 26 to secure the same to the conveyor. 5 These links in addition to preventing stretching or distortion of the receptacles 21, when they are filled with bottles of beverage or the like, also serve, by virtue of their extension across the open rear ends of the receptacles, as stops for preventing bottles of beverage from projecting outwardly of the back of receptacles 21 of the conveyor.

In Fig. 8 of the drawings I have shown a continuous conveyor comprising a plurality of bottle receptacles constructed and connected together as hereinbefore described. The conveyor, generally represented by the reference character 30, is draped or looped over a plurality of idler pulleys 31 and over at least one driving sprocket 32. The pulleys 31 and sprocket 32 may be mounted on the inner side of a back wall of a compartment of a cabinet in which the bottled beverages are to be stored and cooled prior to being dispensed through a door or window in the front wall of the cabinet. Such a door or window may be coin controlled and the conveyor may be progressively moved or indexed to bring a bottle to be dispensed into alignment with the dispensing door or window in response to the manual operation of a leverage device or the like as is well known and conventional in the art. Since walls of the metal receptacles contact or closely embrace bottles located therein the outwardly flared lips 19 and 19a on members 11 and 11a respectively of the receptacles 21 serve to guide the bottles into the cylindrical receptacles during the act of filling the receptacles 21 of the conveyor 30.

From the foregoing it should be apparent that I have provided an improved conveyor and one that is constructed to form cylindrical bottle-receiving and carrying receptacles from companion or identical semi-cylindrical members. The use of identical members, turned and rotated as herein described to form the bottle receptacles 45 simplifies the conveyor structure and requires the making of only a single punching and forming die for producing the members constituting the bottle receptacles. This feature together with the formation of the bottle receptacles from sheet metal and the locking of members of the receptacles to one another by a means that also forms a hinge between adjacent bottle receptacles greatly reduces the cost of manufacturing conveyors.

55 While the form of embodiment of the invention as herein disclosed, constitutes a preferred form, it is to be understood that other forms might be adopted, as may come within the scope of the claims which follow.

60 What is claimed is as follows:

1. In combination, a plurality of substantially cylindrical bottle receiving and carrying receptacles, means connecting said receptacles in continuous side by side relation to provide an endless conveyor with a hinge between each receptacle thereof, each receptacle of the endless conveyor including two elongated substantially semi-cylindrical identical sheet metal members, each of said identical members having integral spaced apart eyelet-like portions projecting outwardly from opposite marginal edges thereof, one of said identical members of each receptacle being turned into face-to-face relation with the other member thereof with the eyelet-like projecting portions on similar marginal edges of each member in align-

ment with one another, and the projecting eyelet-like portions on said members receiving said receptacle connecting means for locking each of the identical members of the receptacles against movement relative to one another.

2. In combination, a plurality of substantially cylindrical bottle receiving and carrying receptacles, means connecting said receptacles in continuous side by side relation to provide an endless conveyor with a hinge between each receptacle thereof, each receptacle of the endless conveyor including two elongated substantially semi-cylindrical identical sheet metal members, each of said identical members having integral spaced apart eyelet-like portions projecting outwardly from opposite marginal edges thereof, one of said identical members of each receptacle being turned into face-to-face relation with the other member thereof with the eyelet-like projecting portions on similar marginal edges of each member in alignment with one another, the projecting eyelet-like portions on said members receiving said receptacle connecting means for locking each of the identical members of the receptacles against movement relative to one another, and a plurality of links having their ends secured to said receptacle connecting means and extending continuously across one end of each receptacle to form a stop for a bottle to be received therein.

3. In combination, a plurality of substantially cylindrical open-end bottle receiving and carrying receptacles, bolts connecting said receptacles in continuous side by side relation to provide an endless conveyor with a hinge between each receptacle thereof, each receptacle of the endless conveyor including two elongated substantially semi-cylindrical identical sheet metal members, each of said identical members having integral spaced apart eyelet-like portions projecting outwardly from opposite marginal edges thereof, the spaced apart eyelet-like projecting portions along one marginal edge of each identical member being staggered relative to those along the opposite marginal edge thereof, one of said identical members of each receptacle being turned into face-to-face relation with the other identical member thereof with the eyelet-like projecting portions on similar marginal edges of each member in alignment with one another, and the projecting eyelet-like portions on said members receiving said receptacle connecting bolts for locking each of the identical members of the receptacles against movement relative to one another.

4. In combination, a plurality of substantially cylindrical open-end bottle receiving and carrying receptacles, bolts connecting said receptacles in continuous side by side relation to provide an endless conveyor with a hinge between each receptacle thereof, each receptacle of the endless conveyor including two elongated substantially semi-cylindrical identical sheet metal members, each of said identical members having integral spaced apart eyelet-like portions projecting out-

wardly from opposite marginal edges thereof, the spaced apart eyelet-like projecting portions along one marginal edge of each identical member being staggered relative to those along the opposite marginal edge thereof, one of said identical members of each receptacle being turned into face-to-face relation with the other identical member thereof with the eyelet-like projecting portions on similar marginal edges of each member in alignment with one another, the projecting eyelet-like portions on said members receiving said receptacle connecting bolts for locking each of the identical members of the receptacles against movement relative to one another, and a plurality of links having their ends secured to said receptacle connecting bolts and extending across one of the open ends of each receptacle to form a stop for a bottle to be received therein.

5. In combination, a plurality of substantially cylindrical bottle receiving and carrying receptacles, means connecting said receptacles in continuous side by side relation to provide an endless conveyor with a hinge between each receptacle thereof, each receptacle of the endless conveyor including two elongated substantially semi-cylindrical identical sheet metal members, each of said semi-cylindrical identical sheet metal members of a receptacle having an outwardly flared lip at each end thereof providing a guide for a bottle adapted to be inserted in said receptacle, each of said identical members also having integral spaced apart eyelet-like portions projecting outwardly from opposite marginal edges thereof, one of said identical members of each receptacle being turned into face to face relation with the other member thereof with the eyelet-like projecting portions on the marginal edge of said one identical member being adjacent to and in alignment with the eyelet-like projecting portions on the marginal edge of said other member, the adjacent eyelet-like projecting portions on the marginal edges of one receptacle being spaced from other adjacent eyelet-like projecting portions thereof for receiving therebetween and in alignment therewith adjacent aligned eyelet-like projecting portions on the marginal edges of members of an adjacent receptacle, and the projecting eyelet-like portions on said members receiving said receptacle connecting means for locking each of the identical members of the receptacles against movement relative to one another.
